FLUID IMPACT PULVERIZER

William Mayo Venable, Pittsburgh, Pa., assignor,
by mesne assignments, to Blaw-Knox Company,
Pittsburgh, Pa., a corporation of Delaware

Application January 4, 1949, Serial No. 69,127

3 Claims. (Cl. 241—39)

1 This invention relates to mills of the impact pulverizer type for grinding various kinds of solid material. More particularly, it relates to a mill in which streams of a gaseous atmosphere in which such material is suspended are directed toward a common point to cause the comminution of such material to desired particle size.

Impact pulverizers or atomizers as they are sometimes called, encompass a number of types and are used to grind a variety of materials. In general, such pulverizers produce fine grinding of such solid material by turbulence in the gaseous atmosphere carrying the fragments of such material or by the colliding action of the streams within the apparatus carrying such material. Thus particles may collide with one another when moving in opposite or converging directions or may collide with some portion of the apparatus and thus be subject to fracture. Further, such particles may impinge upon one another or upon a portion of the apparatus with glancing blows and be reduced in size by attrition.

In mills of the type with which this invention is concerned, these particles are entrained in the gaseous atmosphere by jets or ejectors directed so as to have a common intersection. In order to grind to a sufficient degree of fineness, the particles are recirculated to such jets until reduced to the desired degree. The gaseous atmosphere is produced and maintained as the consequence of the operation of the jets with superheated steam or compressed air. When the nature of the material to be ground requires it, other compressed gases may be used. These gaseous fluids, inclusive of such vapors as may be present, inspirate the particles of solid material which are to be ground and cause them to be suspended in the streams of gaseous fluid and particles so created.

In the pulverizing of coal or other particles, it frequently happens that particles which have already been ground to the predetermined desired degree of fineness remain in the streams, being recirculated and thus are subject to unnecessary regrinding with the coarser particles which are also borne in the stream. Since for each type of material it is desirable that the particles be reduced only to that degree of fineness which will exclude particles coarser than a certain size, particles finer than that certain maximum size, become, in certain cases, undesirable because it is wasteful of power and reduces the capacity of the mill or because the use of which the ground particles are to be put renders a minimum size as well as a maximum size desirable. These diffi-

culties are overcome in the mill of this invention. In this invention the parts of the apparatus are so arranged and proportioned and are of sufficient variety to circulate the material with a minimum expenditure of power to separate toward a common point to cause the comminution of coarser material for recirculation from finer material as adequately as practicable and to avoid the grinding of material excessively beyond a minimum size considered most desirable. Further, in the mill of this invention a wide range of materials of different character can be ground to predetermined particle size. Such materials would include solid fuels such as coal and coke of varying degrees of hardness. This invention is also applicable to the pulverization of materials having special chemical or physical properties such as grinding abrasives, insecticide powders, paper pulp, powder catalyst for hydrocarbon conversion and many others. Other objects and advantages of this invention will be apparent from the following description and from the drawings, in which,

Figure 1 is a vertical view in cross section of a mill made in accordance with this invention, with its return passages removed, and of a separator associated therewith;

Figure 2 is a view in cross section taken along line II—II of Figure 1;

Figure 3 is a view in cross section taken along line III—III of Figure 1 and showing the return passages;

Figure 4 is a vertical view in cross section of the separator and of a feeding means for the mill of this invention taken at right angles to the view shown in Figure 1;

Figure 4A is a view in cross section taken along line IVA—IVB of Figure 4;

Figure 5 is a view taken along line V—V of Figure 3;

Figure 6 is a vertical view in cross section of another embodiment of this invention;

Figure 7 is a view in cross section taken along line VII—VII of Figure 6;

Figure 8 is a plan view of one-half of the embodiment shown in Figure 6; and

Figure 9 is a vertical view in cross section taken along line IX—IX of Figure 8.

Referring to the preferred embodiment shown in Figures 1 to 5, a cylindrical casing 10 is composed of a number of ringlike sections either bolted or welded together in leakproof fashion. Casing 10 together with bottom 11 and a top plate 12 define a grinding chamber 13 in which there is a false bottom 14. Around the lowermost section of casing 10 there are four circular

openings 15 through each of which a nozzle 16 projects. Each nozzle 16 is held in a block 17 threadably connected to a plate 18 which is bolted in sealed engagement with an annular rim 19 welded to casing 10 around each opening 15. Superheated steam or compressed air is supplied to nozzles 16 through the respective pipes 20. For grinding coal superheated steam is usually supplied to nozzles 16. Nozzles 16 are horizontally directed toward a common intersection, the point center of which lies on the vertical axis of chamber 13.

Each nozzle 16 is provided with a coaxially positioned barrel 21 pointing toward said common intersection and spaced in advance of the respective nozzle 16 an amount which provides an annular inlet 22 which constitutes the inspiration zone for each jet or ejector comprising a nozzle 16 and its attendant barrel 21. Each barrel 21 is affixed and held in place in the bore of a bracket 23 fastened to bottom 14. Connecting all of the inspiration zones 22 there is a common annular enclosure 24 formed in chamber 13 by an annular top plate 25 and an inner cylindrical wall 26 through which the foreparts of barrels 21 project. In plate 25 there are a series of restricted openings 27 corresponding in number to the number of inspiration zones 22 and located directly above such zones respectively. Each opening 27 has a scoop 28 associated therewith and adapted to direct particles touching the inside of said scoop into and through said opening.

A baffle plate 29 is located in a horizontal plane above the respective barrels 21, where it is held in spaced relation to said barrels and plate 25 by legs 30. Each leg 30 is welded or otherwise fastened respectively to a barrel 21 and baffle plate 29. While baffle plate 29 is a circular disc in the embodiment shown, it may be made rectangular or in any other shape for the purpose of directing the material that may come in contact with it outwardly through an annular passage 31 respectively between plates 25 and 29. This passage 31 must be of sufficient area to permit the partially ground material to pass through with enough gaseous fluid to carry it but must not be so large that the fluid flow through passage 31 is too small to retain the larger fragments in suspension. In each case, passage 31 must be designed for the particular kind of material to be ground.

A wear plate 32 is affixed to baffle 29 on the top side thereof in the center. This wear plate 32 is adapted to prevent undue wear of baffle 29. The material of which wear plate 32 is made may be of a yielding material to minimize abrasion or of any material suitable for use with the particular character of the material to be ground. Yet, as are all of the parts of the apparatus, it must also be designed to withstand all temperatures and other factors which will be encountered in operation. Four curvilinear vanes 33 are set in baffle 29 and extend above and below the two surfaces thereof. Vanes 33 constitute upstanding and depending walls running from wear plate 32 to the outer edge of baffle 29 in the manner of curved equally spaced spokes on a wheel. Thus, the gaseous streams of gaseous fluid carrying particles of solid material of different sizes leaving an impact zone 34 generally defined by wall 26, bottom 14 and baffle 29, will be given a rotational or centrifugal motion by the depending portion of vanes 33 in addition to that already existing in the chamber as

a consequence of the portions of vanes 33 projecting above baffle 29. This rotation in one direction relative the axis of chamber 13 imparts to the gaseous atmosphere and suspended particles in the chamber a movement which centrifuges the larger of the entrained particles toward the lower portion of casing 10. In addition, this motion centrifuges the finer material toward the upper portion of casing 10 and facilitates the removal of as much thereof as possible from the gaseous fluid which is to be recirculated through barrels 21. Scoops 28 are inclined in a direction counter to the direction of motion imparted by vanes 33 and thus collect such larger particles for recirculation through inspiration zones 22 and regrinding.

A housing 35 is located in the center of the top of plate 12. This housing supports a nozzle block 36 in which a nozzle 37 is threaded. Housing 35 also supports a barrel 38 spaced from nozzle 37 to provide an annular inlet 39 which is the inspiration zone for the feed jet or feed ejector which comprises nozzle 37 and barrel 38. Gaseous fluid to operate nozzle 37 is supplied through a line 40.

Housing 35 has an opening on one side thereof of adjacent inspiration zone 39, to which opening there is connected a feed conduit 41, as shown particularly in Figure 4. A bracket 42 fastened to the edge of plate 12 supports conduit 41. The outer end of conduit 41 is opened for connection to a flared hopper 43 to which fresh material is supplied. A screw conveyor 44 is rotatably supported in conduit 41 and is turned by a sprocket 45 on the shaft thereof for material advancing engagement with the inside of conduit 41. Intermediate the ends of conduit 41 in advance of hopper 43 there is a pipe connection 46 leading to a separator.

An annular hood 47 is centrally supported on the underside of plate 12. This hood includes a frusto-conical recess 48 around the outer portion thereof, the outer peripheral side 49 of which is somewhat longer than the inner peripheral side 50. Hood 47 also includes a cylindrical center portion 51 spaced equally from side 50 and forming an inner annular passage 52. Center portion 51 is also fastened to the underside of plate 12 and extends downwardly a distance substantially equal to the vertical projection of side 50. Passage 52 is connected through openings in plate 12 with four return passage conduits 53 composed of pipe sections forming a reentrant loop as shown in Figure 5, connected directly into auxiliary annular enclosure 24 through the lower section of casing 10. A butterfly damper valve 54 is rotatably supported by a pin 55 in each conduit 53. The conduits 53 are of relatively large cross-sectional area, which area can be effectively changed to obtain the desired velocity of gaseous fluid with such entrained solid material as may be therein to enclosure 24 by adjustment of the setting of damper 54. In some cases dampers 54 can be entirely closed to achieve particular velocity conditions through passage 31 and in the remaining portions of the apparatus. Two uptakes 56 are connected with chamber 13 through plate 12 adjacent the uppermost section of casing 10. In this position uptakes 56 are shielded at least partially by side 49 of hood 47. In addition, the aggregate cross-sectional area of uptakes 56 is substantially less than the aggregate cross-sectional area of conduits 53.

A separator 57 is joined to the upper ends of

uptakes 56. Separator 57 comprises a funnellike outer annular passage 58 and a concentric inner passage 59. These passages open into each other at their respective upper ends through an opening 60 in which there are directing vanes 61 curving about the central axis of separator 57 to impart rotary motion to the stream of gaseous fluid and entrained ground material rising in passage 58. The top of both passages is closed by a plate 62 in the center of which there is a riser pipe 63 which projects downwardly into inner passage 59 below opening 60. A bell type shield 64 is suspended by brackets 65 from the lower end of riser 63. Hence, as the stream rising in passage 58 moves downwardly after passing through opening 60 ground or pulverulent material, suspended in the gaseous fluid of the stream and meeting specifications of predetermined particle size, pass into riser 63 and out of the grinding mill and separator. The coarser and heavier ground material in that stream moves downwardly through inner passage 59 and a downcomer 66 connected at the lower end thereof by a leakproof sleeve 67 with pipe connection 46. Thus such coarser and heavier particles of the ground material pass into conduit 41 and are admixed with fresh or untreated material as screw conveyor 44 continues to supply the inspiration zone 39 of the feed jet. The specific combination and arrangement of uptakes 56, separator 57 and conduit 41 are a part, not of this invention, but of the invention set forth in United States patent application Serial No. 69,103, filed on even date herewith, in the name of Alfonse M. Andries.

It is evident that the proportions of the various parts and openings of apparatus made in accordance with this invention are matters within the scope of engineering skill. Thus the proportions of the baffle parts including the passage 31 and of the areas of return passages 53, uptakes 56, the parts of separator 57 and of the feeding mechanism as well as the restricted openings 27 and the dimensions of chamber 13 will be determined in the light of the particular qualities of the material to be ground, the nature of the gaseous fluid or fluids used in the respective jets, the pressures, temperatures and the like to be encountered and the size of the apparatus. Such particulars constitute the field of process engineering and in such connection all of the drawings in this case are to be considered as merely diagrammatic. Moreover, under some conditions, certain kinds of material will not require the use of any vanes 33 or such vanes may only be necessary on one side or the other of baffle 29. All portions of the apparatus will also be suitably insulated where necessary to prevent undue loss of heat.

An alternative embodiment of this invention is shown in Figures 6 to 9 inclusive. Such an alternative embodiment is useful in existing plants in which the available space is limited especially as to head room. In this alternative embodiment, a casing 10' including a top plate 12' and a bottom 14' define a chamber 13'. Except as otherwise noted, the various and respective parts of the apparatus in the alternative embodiment are numbered with the same references primed, as the references used in describing the preferred embodiment in Figures 1 to 5 inclusive, serve the same purposes and have the same advantages.

It will be noted that the grinding jets or ejectors comprising nozzles 16' and barrels 21' are

tilted upwardly away from the horizontal. The purpose of this is to prevent an undue downward pressure in impact zone 34' which might otherwise obstruct the entry of material propelled into impact zone 34' of chamber 13' as distinguished from the preferred embodiment in which the material is jetted into chamber 13 outside of impact zone 34. The feed jet in the alternative embodiment comprises a nozzle 37' and a barrel 38' which forces the material into a conduit 70 opening into impact zone 34' through bottom 14'. The wear plate 32' in the alternative embodiment is fixed in place and supported on legs 71 and serves not only as a wear plate but also as a baffle apart from baffle plate 29'. Barrel 38' has a Venturi bore 72 lined with refractory blocks 73, a type of provision which may also be made in barrel 38 of the preferred embodiment. Another purpose is served by the upward inclination of nozzle 16' and barrels 21' in that such positioning tends to increase the pressure of the stream flowing outwardly through passage 31', thereby assisting in the removal of solid material, including the feed entering through conduit 70, out of impact zone 34'.

In the alternative embodiment baffle 29' is made with a conical top 74 which produces movement of any stream downwardly impinging thereon toward the inner walls of casing 10'. Rotary motion is imparted to the stream flowing out of impact zone 34 by curvilinear vanes 33' which also serve to support baffle plate 29' on the upward extension of circular wall 26'.

Hood 47' in the alternative embodiment is 35 an annular horizontal plate having a central passage 52' instead of an annular passage 52 as in the preferred embodiment. Because of this construction a single damper plate 54' suffices and is raised and lowered by a threaded rod 75, having a hand wheel 76 at the upper end thereof, and threadably engaging a sleeve 77. Sleeve 77 is rigidly affixed to a cupola 78 which extends through plate 12' by which it is supported. Cupola 78 supports hood 47' and cylindrical wall 51'. Return passage conduits 53' are connected to the interior of cupola 78 through openings in the side wall thereof and lead recirculating gaseous fluid with such entrained material therein to the annular auxiliary enclosure 24'.

50 Finer ground material rotating about the inner periphery of casing 10' passes out of chamber 13' through an outlet 56' corresponding to uptakes 56 in the preferred embodiment. Outlet 56' is connected to chamber 13' in a tangential manner counter to the direction of rotation imparted by vanes 33'. This horizontal tangential mounting of outlet 56' assists in reducing the overall height of the alternative embodiment, as does the bottom feeding arrangement through

60 conduit 70. A suitable separator, not shown, is connected to outlet 56' and the rejected material from that separator may be returned to conduit 41' as is done in the preferred embodiment. Brackets 23' support, in the alternative embodiment, the entire grinding jet assembly by being welded in the corresponding openings in the lowermost section of casing 10'. Brackets 23' are recessed at 79 to provide the necessary opening between each inspiration zone 22' and auxiliary enclosure 24'.

Although I have illustrated and described but a preferred practice and embodiments of the invention, it will be recognized that changes in the procedure and structural details may be made

without departing from the spirit of the invention or the scope of the appended claims.

I claim:

1. Impact apparatus for pulverizing solid material, comprising in combination, a chamber, an impact zone in the lower portion of said chamber, a plurality of grinding jets directed toward a common intersection in said impact zone, said grinding jets having inspiration inlets outside said zone, an annular enclosure in said chamber enclosing said inspiration inlets, means for feeding solid material borne in a gaseous fluid into said chamber, a baffle spaced from and substantially covering said impact zone, said baffle being interposed between said means and said plurality of jets and defining therewith a velocity exit from said impact zone, curvilinear vanes on said baffle, said vanes curving in one direction and adapted to centrifuge streams of gaseous fluid and particles around the outer portion of said chamber, a hood centrally located in said chamber above said baffle, a return passage directly connecting said hood and said annular enclosure, and an outlet adjacent the periphery of said chamber at the top thereof and adapted to be partially shielded by said hood, whereby coarse particles are carried to said inspiration inlets for grinding in said impact zone, finer particles of not greater than predetermined size are carried out through said outlet and gaseous fluid with less entrained material therein is circulated through said return passage.

2. Impact apparatus for pulverizing solid fuel, comprising in combination, a chamber, a well defining an impact zone in the lower portion of said chamber, a plurality of grinding jets directed toward a common intersection in said impact zone, said grinding jets having inspiration inlets outside the outer periphery of said wall, an annular plate defining with said wall an annular enclosure for said inspiration inlets, means for feeding solid material borne in gaseous fluid into said chamber adjacent said impact zone, a baffle above said common intersection and between the same and said means, said baffle being spaced from and substantially covering said impact zone to define with said wall an annular exit therefrom, means adjacent said annular exit for imparting rotational force to streams of gaseous fluid and particles exiting from said impact zone, an outlet for particles of sufficient fineness adjacent the periphery of said chamber in the upper portion thereof, and a return outlet nearer the vertical

axis of said chamber for returning gaseous fluid to said annular enclosure around the outside of said chamber.

3. Apparatus for pulverizing solid material, comprising in combination, a closed chamber, a generally vertical wall adjacent the bottom of said chamber and surrounding an unobstructed impact zone therein, a plurality of ejectors for grinding and recirculating material to be ground within said chamber, said ejectors being generally horizontal and directed toward a common intersection within said impact zone, said ejectors having nozzles and barrels, said barrels extending through openings in said wall, the inlets to said barrels being outside said wall in an auxiliary annular enclosure, an annular plate covering the top of said enclosure and having restricted openings therein, a baffle plate closely spaced relative to the upper edge of said wall to provide therewith an annular outlet passage from said impact zone into the remainder of said chamber, said annular outlet passage being adjacent said restricted openings, radially offset vanes adjacent said annular outlet passage to impart rotational force in one direction to streams of gaseous fluid and solid particles leaving said impact zone, scoops adjacent said restricted openings extending in a direction opposed to the direction of rotation imparted by said vanes, means for feeding a stream of gaseous fluid material to be ground into said chamber adjacent said impact zone, and an outlet pipe connected to the upper outer portion of said chamber to remove gaseous fluid suspended particles of ground material therethrough.
